UNITED STATES PATENT OFFICE.

WILLIAM THIOMMEN, OF PORT WASHINGTON, WISCONSIN, ASSIGNOR TO THE WISCONSIN CHAIR COMPANY, OF SAME PLACE.

DESIGN FOR A CHAIR.

SPECIFICATION forming part of Design No. 28,819, dated June 7, 1898.

Application filed May 10, 1898. Serial No. 680,325. Term of patent 7 years.

To all whom it may concern:

Be it known that I, WILLIAM THIOMMEN, a citizen of the United States, residing at Port Washington, in the county of Ozaukee and State of Wisconsin, have invented and produced a new and original Design for Chairs; and I do hereby declare the following to be a full, clear, and exact description of the same, reference being had to the accompanying drawings, forming a part thereof.

In the said drawings, Figure 1 is a view in end elevation, and Fig. 2 a view in front or rear elevation, of a chair embodying my new design.

My design relates to the new and original shape or configuration of the article.

The leading or essential feature consists in the unitary design for a chair made the subject of illustration, comprising four legs flaring outwardly and downwardly disposed, so that the upper ends of said legs are all nearer together than the lower ends thereof, in connection with the shape of the seat of the chair, which is in the general form of a double ogee with straight end pieces and curved front and rear pieces, the shape of the upper surfaces of the said front and rear pieces conforming to the shape of the seat proper located just above said pieces, while the under surfaces of said front and rear seat-pieces are straight at each end and semicircular at the center and ogee-shaped between the center and ends. The legs are connected by horizontally-disposed rounds or cross-pieces, those that connect the legs at front and rear being of greater

length and arranged at a higher plane than those that connect the legs at each end.

Four posts are arranged to extend upwardly above the seat, and these posts flare or incline upwardly and outwardly, so that said posts are all nearer together at their lower ends than at their upper ends, the arrangement of the posts being therefore just the opposite of the arrangement of the legs, and said posts are connected above their tops by cross-bars horizontally disposed and transverse to the greatest length of said chair, the ends of said cross-bars extending beyond the said tops of the said posts, while at each end of said chair there are a series of upright rods, all flaring outwardly from bottom to top, extending between the end rounds or cross-pieces of the chair and the horizontal top cross-bars, the center upright rod at each end extending in a straight line from bottom to top and the rods on each side thereof flaring out laterally from bottom to top.

Having described my invention, what I claim as new, and desire to secure by Letters Patent, is—

The design for a chair, substantially as herein shown and described.

In testimony that I claim the foregoing I have hereunto set my hand, at Port Washington, in the county of Ozaukee and State of Wisconsin, in the presence of two witnesses.

WILLIAM THIOMMEN.
